UNITED STATES PATENT OFFICE

1,988,737

LIQUID SPRAYER

José Alonso Jauregui, Chicago, Ill.

Application January 12, 1934, Serial No. 706,362

15 Claims. (Cl. 4-7)

The following is a specification, the same being a continuation in part of application Serial No. 628,279, filed August 11, 1932.

This invention relates to a sanitary liquid sprayer of portable character adapted to be fitted and used in association with a toilet seat and a nearby water faucet for the purpose of providing easy and convenient means for the purpose of spraying water or other liquid upon certain portions of the body or for use as a douche either externally or internally.

The device of the present invention is designed to fit within the bowl of a toilet and to be supported from the rim of the bowl and below the seat and to discharge the water or other liquid upwardly so as to permit the use thereof under circumstances which would otherwise preclude the use of such a device and without danger of wetting the clothing of the user or of projecting water upon the floor or upon surrounding objects, so that the device as a whole may be readily fitted for use under conditions which would otherwise preclude the possibilities of using a sprayer.

The present invention is directed to the device as a whole and to the means provided for suspending it in position within the toilet bowl; to the means provided for attachment to a supply of water or liquid; to the means employed for the utilization of soap or medicinal preparations within the tank of the sprayer and for internally projecting the water in such a way as to bring the same into intimate contact with the soap or the like; to the means provided for regulating the volume of the water discharged upwardly toward the body of the user; to the means for adjusting the position of the tank below the toilet seat, and to the general arrangement of the device as a whole.

Further objects and details will appear from a description of the invention in conjunction with the accompanying drawing, wherein,—

Figure 1 is a sectional elevation of a toilet showing in elevation the sprayer of the present invention;

Fig. 2 is a sectional elevation of the sprayer, showing the same with the valve adjusted to discharge the entire volume of water upwardly, the section being taken on line 2-2 of Fig. 1;

Fig. 3 is a similar view of the sprayer showing the valve adjusted to discharge a portion only of the water upwardly and to waste the remainder into the toilet bowl;

Fig. 4 is a similar view showing the adjustment required to waste the entire volume of water;

Fig. 5 is an enlarged detail showing the method of connecting one of the suspending arms of the tank;

Fig. 6 is a cross sectional detail taken on line 6-6 of Fig. 2; and

Fig. 7 is a cross sectional detail taken on line 7-7 of Fig. 5.

The sprayer of the present invention is designed for use in connection with a toilet bowl 10 having the usual rolled-over rim 11, a toilet seat 12, and a cover 13. The seat, as is customary, is provided with hinges 14 and the usual cushioning lugs (not shown), which bear against the rim of the bowl and afford a slight clearance between the two. The sprayer comprises a cup-shaped tank 15, the base 16 of which is preferably of semi-spherical or bowl shape, and affords a receptacle for a cake of soap, medicinal preparation or the like.

The tank is surrounded by a suspending band in the form of a split ring consisting of sections 17-17, which terminate at each end in ears 18 which are drawn together by a headed tubular bolt 19 which coacts with a headed inner bolt 20 threaded into the tubular bolt. Each pair of ears embraces the inner head 21 from which extends the inner section 22 of a suspending arm, which also comprises an outer section 23 which is telescoped into the inner section, and the outer section is adapted to rest upon the rolled rim of the toilet bowl, so that the two suspending arms in conjunction will support the tank in a medial position within the bowl and below the seat which, under the weight of the occupant, will clamp the suspending arms between the seat and the rim of the bowl, thereby holding the tank firmly in its medial position.

The method of clamping the split ring sections 17-17 of the suspending band is one which permits the tank to be adjusted vertically within limits to secure the desired elevation for the discharge of the water or other liquid, and in order to hold the suspending arms in proper position each head 21 on its upper side is provided with a stop finger 24 which abuts against the wall of the tank and serves to limit the upward adjustment of the arms and hold the same in the obliquely upwardly standing position as shown.

Water under pressure from a nearby source is supplied to the tank through a flexible tube 25 provided at its free end with a connection 26 adapted to fit over the water faucet of a bath tub or wash bowl, and the inner end of the tube is fitted on to a nipple 27 extending from the forward side of the tank at a medial position vertically and connecting with an inner nozzle 28 provided on each side with obliquely upwardly discharging ports 29 and on its base with a discharge port 30, which arrangement is desirable in that water is discharged downwardly into the bowl-shaped interior of the tank and laterally around the wall thereof in such a way

as to produce a circulatory movement of the water around the base and walls of the tank, thereby bringing the inrushing water intimately into contact with the surface of the cake of soap or the like to produce the scouring action thereon required to obtain a soapy or medicated solution.

The cylindrical top of the tank is closed by means of a cap 31 provided with an exteriorly threaded marginal flange 32, and the cap carries a cross tube 33, the forward end of which is closed by a threaded plug 34, which is threaded through the center to receive a steeply pitched adjusting screw 35 which is carried by a valve stem 36 terminating in a knurled button 37, which extends forwardly from the top of the tank and in convenient position to permit the user to adjust the valve stem in and out to regulate the discharge of water.

The inner end 38 of the valve stem is provided with spaced valve disks 39 and 40, which fit snugly within the forward bore 41 of the tube, which forward bore communicates with a rear bore 42 of lesser diameter, affording a shoulder or abutment 43 for limiting the inward movement of the adjusting valve. The rear end of the tube terminates in a downturned elbow 44 for the discharge of waste water downwardly into the toilet bowl.

The tube 33 is provided on its under side with an inflow port 45 communicating with the tank and on its upper side with an outflow port 46 which is surrounded by an interiorly threaded flange 47 adapted to receive the neck 48 of a spray cap 49 which is provided on its top wall with spray ports 50. The arrangement, however, is one which permits the spray cap to be removed and the conventional type of hard rubber nozzle to be fitted in place as desired, or when an internal douche is to be administered.

The spacing of the valve disks 39 and 40 is such as to permit all of the water or other liquid to be discharged upwardly through the ports 45-46 and through the spray cap when the regulating valve is adjusted as in Fig. 2, or to permit the water flow to be divided as in Fig. 3, or to be wasted as in Fig. 4, depending upon the adjustment of the valve, and the steep pitch of the regulating screw 35 permits such adjustments to be readily made by the user from a convenient position in front of the tank and by a few turns of the adjusting button 37.

The method of pivoting the suspending arms to the tank is one which permits the arms to be swung downwardly into parallel relation to the axis of the tank when it is desired to pack away the sprayer, and the device as a whole is so arranged that it can be instantly removed from the toilet bowl and the flexible tube rolled up into a small compass so that the sprayer may be readily packed into a traveling bag or suit case and quickly adjusted for use as occasion may require.

By directing the water upwardly from the medial position within the toilet bowl, the danger of discharging any water beyond the confines of the toilet bowl is obviated, and the method of suspending the device from arms which rest upon the rim of the toilet bowl and are clamped thereon by the weight of the occupant obviates any danger of displacement or mal-adjustment during use, and permits the device to be safely and conveniently used under conditions which would preclude the use of an ordinary douche or sprayer. The amount of

water discharged and the force of the discharge can be readily regulated both by the adjustment of the bath room water faucet and by the adjustment of the regulating valve, so that any desired degree of pressure may be obtained and the overflow and drainage from the douche will be carried away without wetting the bath room or the clothing of the user.

While it is preferred to make the tank and the remaining features of the device of metal, hard rubber, or bakelite, they may of course be made of other materials if desired.

Although the invention has been described with particularity as to detail, it is not the intention to limit the invention to the details shown, since modifications thereof may be made without departing from the spirit of the invention.

I claim:

1. In combination with a toilet, a sprayer comprising a tank, suspending means adapted to engage the rim of the toilet and to hold the tank in fixed position medially suspended beneath the seat, a discharge member upon the top of the tank for discharging liquid upwardly therefrom, and means for supplying liquid to the tank.

2. In combination with a toilet, a sprayer comprising a tank, supporting arms having their inner ends secured to the tank on opposite sides thereof and with their outer ends resting upon the rim of the toilet for medially suspending the tank in fixed position beneath the toilet seat, means carried by the tank for discharging liquid upwardly therefrom, and means for supplying liquid to the tank.

3. In combination with a toilet, a sprayer comprising a tank, supporting arms having their inner ends pivotally secured to the tank on opposite sides thereof and with their outer ends resting upon the rim of the toilet for medially suspending the tank in fixed position beneath the toilet seat, means carried by the tank for discharging liquid upwardly therefrom, and means for supplying liquid to the tank.

4. In combination with a toilet, a sprayer comprising a tank, supporting arms having their inner ends secured to the tank on opposite sides thereof and with their outer ends resting upon the rim of the toilet for medially suspending the tank in fixed position beneath the toilet seat, means carried by the tank for discharging liquid upwardly therefrom, means for supplying liquid to the tank, and a control valve adapted to regulate the volume of liquid discharged from the tank.

5. In combination with a toilet, a sprayer comprising a tank, supporting arms having their inner ends pivotally secured to the tank on opposite sides thereof and with their outer ends resting upon the rim of the toilet for medially suspending the tank fixedly beneath the toilet seat, means carried by the tank for discharging liquid upwardly therefrom, means for supplying liquid to the tank, and a control valve adapted to regulate the volume of liquid discharged from the tank.

6. In combination with a toilet, a tank provided with a cover carrying a tube provided with an open end adapted to discharge downwardly into a toilet bowl, the cover being provided with a perforation establishing communication between the tank and the tube, a spray device mounted upon the exterior of the cover and communicating with the interior of the tube and perforated to afford an upward discharge of

- liquid from the tube, means for suspending the tank with the cover carried thereby medially below the rim of the toilet seat, and means for supplying liquid to the tank.
- 5 7. In combination with a toilet, a tank provided with a cover carrying a tube provided with an open end adapted to discharge downwardly into a toilet bowl, the cover being provided with a perforation establishing communication between the tank and the tube, a spray device mounted upon the exterior of the cover and communicating with the interior of the tube and perforated to afford an upward discharge of liquid from the tube, a control valve within 10 the tube adapted to be adjusted to regulate a relative amount of liquid passing through the spray member and through the discharge end of the tube, means for suspending the tank with the cover carried thereby medially below the rim 15 of the toilet seat, and means for supplying liquid to the tank.
- 10 8. In combination with a toilet, a tank provided with a cover carrying a tube provided with an open end adapted to discharge downwardly into a toilet bowl, the cover being provided with a perforation establishing communication between the tank and the tube, a spray device mounted upon the exterior of the cover and communicating with the interior of the tube and perforated to afford an upward discharge of liquid from the tube, means for suspending the tank with the cover carried thereby medially below the rim of the toilet seat, and means for regulating the amount of liquid discharged through 20 the spray member, and means for supplying liquid to the tank.
- 15 9. In combination with a toilet, a liquid sprayer comprising a tank, a spray member carried by the tank and communicating therewith and adapted to discharge liquid upwardly, means for admitting liquid to the tank for discharge through the sprayer, and upwardly and outwardly extending supporting arms having their inner ends secured to the tank in a manner to permit vertical adjustment and having their outer ends supported upon the rim of the toilet for holding the tank in fixed position medially below the toilet seat.
- 20 10. In combination with a toilet, a liquid sprayer comprising a tank, a spray member carried by the tank and communicating therewith and adapted to discharge liquid upwardly, means for admitting liquid to the tank for discharge through the spray member, means for regulating the amount of liquid discharged through the spray member, and upwardly and outwardly extending supporting arms having their inner ends secured to the tank in a manner to permit vertical adjustment and having their outer ends supported upon the rim of the toilet for holding the tank medially below the toilet seat.
- 25 11. In combination with a toilet, a liquid sprayer including a spray member, means connected with the spray member and extending upwardly and outwardly therefrom and adapted to be supported upon the rim of a toilet bowl and to hold the spray member in fixed relation below the rim and in position to discharge liquid upwardly, and means for supplying liquid to the spray member.
- 30 12. In combination with a toilet, a tank provided with a cover carrying a transverse tube provided with an open downwardly turned end adapted to discharge downwardly into a toilet bowl, the tube being provided with a smaller bore at said downwardly turned end and a larger bore at the opposite end affording a shoulder or abutment, a plug threaded into the opposite end of the tube, a valve carried by the tube and having a steeply pitched screw section threaded through the plug for adjustment therein, the valve being provided at its outer end with a handle and being provided at its inner end with spaced discs operable within the larger bore of the tube, the tube section having the larger bore being provided with a port communicating downwardly to the interior of the tank and being provided with a port for the discharge of liquid upwardly, a spray member communicating with the last named port, the spacing of the valve discs with respect to the ports being such as to permit upward discharge of all of the liquid in one extreme position of adjustment and waste discharge of all of the liquid in another extreme 20 position of adjustment and a division of the discharge in intermediate positions of adjustment, and means carried by the tank for suspending the same medially below the rim of the toilet seat.
- 35 13. In combination with a toilet including a bowl and a seat, a liquid sprayer comprising a tank, a spray member carried by the tank and communicating therewith and adapted to discharge liquid upwardly, means for admitting liquid to the tank for discharge through the spray member, means for regulating the amount of liquid discharged through the spray member, and supporting arms having their inner ends pivotally secured to the tank and provided with stops positioned to limit the upward swing of the arms and hold the arms in obliquely upwardly extending radial position to bring their ends into position between the rim of the bowl and the toilet seat for holding the tank medially below the 40 toilet seat.
- 40 14. In combination with a toilet including a bowl and a seat, a liquid sprayer comprising a tank, a spray member carried by the tank and communicating therewith and adapted to discharge liquid upwardly, means for admitting liquid to the tank for discharge through the spray member, means for regulating the amount of liquid discharged through the spray member, supporting arms having their inner ends pivotally secured to the tank and provided with stops for limiting the upward swing of the arms and for holding the arms in radial position to bring their ends into position between the rim of the bowl and the toilet seat for holding the tank medially below the toilet seat, and means for vertically adjusting the pivotal mountings with respect to the tank to adjust the vertical position of the tank with respect to the toilet seat.
- 45 15. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
- 50 16. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
- 55 17. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
- 60 18. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
- 65 19. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
- 70 20. In a sprayer of the class described, the combination of a tank provided with a bowl-shaped bottom and provided on its top with means for discharging a spray upwardly, means for supporting the tank within the bowl of a toilet, a flexible tube connected at its inner end to the tank and having at its outer end a member adapted to connect with a faucet for supplying liquid under pressure to the tank, a fitting within the tank connected with the inner end of the tube and perforated to discharge water against the inner wall of the tank in proper direction to produce circulatory motion of water therein, and valve means for regulating the discharge of water from the tank.
